UNITED STATES PATENT OFFICE

96,525

DESIGN FOR A VACUUM CLEANER

Erik Gustaf Ahnström, Stockholm, Sweden, assignor to Electrolux Corporation, Dover, Del., a corporation of Delaware

Application November 30, 1934, Serial No. 54,192
In Germany August 23, 1934

Term of patent 14 years

To all whom it may concern:

Be it known that I, Erik Gustaf Ahnström, a subject of the King of Sweden, residing in Stockholm, Sweden, have invented a new, original, and ornamental Design for a Vacuum Cleaner, of which the following is a specification, reference being had to the accompanying drawing, forming part thereof.

The figure is a perspective view of a vacuum cleaner, showing my new design.

An important feature of the design resides in the polygonal shape of the end of the casing.

I claim:

The ornamental design for a vacuum cleaner, as shown and described.

ERIK GUSTAF AHNSTRÖM.
